US0D1033686S

(12) **United States Design Patent** (10) **Patent No.:** **US D1,033,686 S**
Polston (45) **Date of Patent:** **** Jul. 2, 2024**

(54) **DRIP EDGE ROOF FLASHING**

- (71) Applicant: **Ross Building Products, LLC**, New Braunfels, TX (US)
- (72) Inventor: **Scott Ross Polston**, New Braunfels, TX (US)
- (73) Assignee: **Ross Building Products, LLC**, New Braunfels, TX (US)
- (**) Term: **15 Years**
- (21) Appl. No.: **29/884,084**
- (22) Filed: **Feb. 7, 2023**

Related U.S. Application Data

- (63) Continuation of application No. 16/453,624, filed on Jun. 26, 2019, now abandoned.
